UNITED STATES PATENT OFFICE.

ALBION D. T. LIBBY, OF ELYRIA, OHIO, ASSIGNOR, BY MESNE ASSIGNMENTS, TO THE GARFORD MANUFACTURING COMPANY, OF ELYRIA, OHIO, A CORPORATION OF OHIO.

COMPOSITE ELECTRIC SYSTEM.

1,139,127.

Specification of Letters Patent. Patented May 11, 1915.

Application filed January 28, 1910. Serial No. 540,571.

To all whom it may concern:

Be it known that I, ALBION D. T. LIBBY, a citizen of the United States, residing at Elyria, in the county of Lorain and State of Ohio, have invented certain new and useful Improvements in Composite Electric Systems; and I do hereby declare the following to be a full, clear, and exact description of the invention, such as will enable others skilled in the art to which it appertains to make and use the same.

My invention relates to composite electric systems in which a telephone and police system is operated over the same system of conductors. More particularly I contemplate providing a system in which I may signal the patrolmen by the use of an attractive signal. This signal is controlled from a special police or main station and is perceptible at a great distance from the substation. By operating the signal the operator at the main station may attract the attention of the patrolmen along the beat. I intend to use the conductors of the combined telephone and police system for operating these signals, making them independent of any auxiliary or separate circuits. I may also control the connection of the signals through a circuit utilizing the conductors of the combined police and telephone system. I also provide means for automatically interrupting the connection over which the lamps are operated, when a subscriber responds. I contemplate interrupting the police signaling system when the signals are operated and provide a pilot or indicator for gaging or testing the condition of the signals at the substations.

Other objects of my invention will be apparent to those skilled in the art, as I have enumerated only those most readily apparent.

My invention will be best understood by reference to the following description when taken in connection with the accompanying illustrations showing several embodiments thereof, while its scope will be more particularly pointed out in the appended claims.

Figure 1 is a diagrammatic representation of one form of my invention. Fig. 2 is a modification. Fig. 3 is a second modification.

Referring now to Fig. 1, I show at A the apparatus which I install at the main or police station and which I shall designate

as the main station. From this extend a plurality of lines which consist of several conductors. One of these lines is shown extending to the two substations C and D. The apparatus shown at these stations I intend to place in police boxes at positions along the streets, or which I may, as will be apparent, install at any place. Each line as shown consists of the conductors 1, 2, 3, and a 4th conductor here shown as the ground, although I do not contemplate being limited to this particular number or kind of conductors. The conductors 1 and 2 serve for the talking mains of a telephone system. The transmitter T and receiver S are shown bridged across these conductors. The alternating current relay R⁵ and a condenser F are also bridged across these two conductors. Owing to the high resistance of the relay R⁵ and the capacity of the condenser F, the telephone or speech currents will not pass through the relay bridge. At each station I show a lamp L and variable resistance Y bridged from the conductor 1 to the conductor 3. This bridge is controlled by the relay R⁵. Legged from the conductor 3 to ground at each station I show a police signal sending device E which is normally an open circuit, but which, when operated, is adapted to be driven by a motor to close and open the circuit in accordance with a code for which it is arranged. I also show legged to ground at each station a key N which has a function to be described. The conductor 3 leads to a relay R¹ at the main station which controls a register or police signal receiving and recording device Q. This relay also controls a circuit to the wagon house. This particular part of the apparatus having no part in my invention, I have not illustrated it, it being fully shown in Fig. 1 of the drawing of my previous application which has matured into the patent above given.

The conductors 1 and 2 lead to the switch springs of the key K which is adapted to connect the main station telephone set M in circuit with the telephone line. The conductor 1 normally leads to the relay R which controls the line signal L³; the conductor 2 normally leading to ground at the main station. At X I show a source of current, in this case, an alternator, which controls relays R⁶ at the substations. The connection of this source of current to the line is con-

trolled by a relay R^4 which is placed in circuit adapted to be closed by the key K^1 . Relay R^4 also controls the circuit of a relay R^2 which in turn is adapted to connect a source of current B^2 in circuit with the lamps L to operate the same. In circuit with the battery B^2 I provide a pilot or indicator, in this case shown as a lamp L^2 . This lamp serves to indicate the condition of the lamps L , as, should any of them be inoperative, the change in brilliancy of the filament of the pilot lamp will indicate the same. The relay R^2 also controls the police signaling circuit to interrupt the same when the source B^2 is connected with the lamps. At R^3 I show a relay in circuit with the source X and which controls a switch in the circuit of relay R^2 . As long as the receivers at the substations are upon the hooks interrupting the telephone bridges thereat, the resistance in the circuit of the source X is sufficient to prevent the energization of the relay R^3 . As soon, however, as a call is responded to at a substation by removing the receiver from the hook, or otherwise lowering the resistance of the circuit of the source X , the current flow in said circuit is sufficient to operate the relay R^3 . The switch in the circuit of R^2 is opened and the relays R^2 and R^4 de-energized which interrupts the circuit of the relays R^2 and the lamps L . It will thus be seen that the current from the source X passes instantaneously through the telephone instruments at the substations. I do not wish to be limited to this form of automatically interrupting the lamp circuit when the called station responds, but may use any other means within the purview of the claims. The apparatus and the functions thereof which are contemplated by my invention, can be best understood by a description of the operation.

The operation is as follows: Should a policeman desire to call a main station to communicate with the chief of police or other person thereat over the telephone, he removes his receiver from the hook H which engages contact 5, closing the circuit as follows: from ground G at the main station—through battery B —relay R —conductor 6—switch 7—8—conductor 9—switch 10—11—conductor 1—substation bridge including the switch hook H , receiver S and transmitter T —the other side of line 2—the switch 12—13—conductor 14—switch 15—16—to ground at G^s . The relay R pulls up its armature 17 closing the switch 17—18 and a circuit through battery B —19 and the lamp L^2 . The attendant noticing the illumination of lamp L^2 operates key K bridging her set M on through the switches 8—20, 15—21. The attendant then communicates with the patrolman over the mains 1 and 2, current being supplied from the source B^4 . At the termination of the conversation the key K is

thrown back and the receiver returned to the hook interrupting the circuits and restoring the system to normal. The patrolman in sending in his signal starts the motor which controls the circuit interrupter E , 70 and a circuit is made and broken as follows: ground G^s —interrupter E —leg 22—conductor 3—switch 23—24—conductor 25—relay R^1 —battery B^3 —ground G^1 . The relay R^1 pulls up its armature 26, closing the circuit of the magnet of the register Q which registers upon a tape the signals sent and closes the circuit of the time stamp, etc. To operate the signals L at the substations, which may be lamps inclosed in the police boxes, adapted, when illuminated, to disperse light through the lenses in the sides of the boxes, the operator throws the key K^1 , closing the following circuit: ground G^s —switch 30—31—conductor 32—relay R^4 —35 battery B^2 —ground G^s . This operates the relay R^4 which pulls down its armatures 11, 12 and 33, closing a locking circuit through itself as follows: ground G^4 —key K^2 —switch 34—35—conductor 36—relay R^2 —30 switch 36—33—relay R^4 —battery B^s —ground G^s . The relay R^4 also closes switches 11—37 and 12—38 connecting the source of current X in circuit with the relays R^5 , the latter being energized over the following: from X —through switch 38—12—over conductor 2—through the relays R^5 —the condensers F at the substations—the conductor 1—switch 11—37—39—relay R^2 —back to X . The relays R^5 are energized, attracting their armatures 40 and closing the switches 40—41 in the signal circuits at the substations. The relay R^3 is not energized, owing to the high resistance of the relays R^5 . The relay R^2 is energized pulling up its armatures 23 and 42, breaking the police signaling circuit at 23—24 and closing the switches 23—43 and 42—44. The following circuit is now completed: from battery B^2 —through the switch 44—42—conductor 39—110 switch 37—11—through the signal bridges at the substations including the lamps L , the switches 41—40, the variable resistances Y —through conductor 3—switch 23—43—the pilot lamp L^2 —variable resistance Y^2 in parallel, back to battery B^2 . The lamps L are all operated over this circuit. Upon the observation of the signal by the patrolman, he goes to the box and takes down the telephone receiver, closing the switch H —5, and bridging the telephone set across the conductors 1, 2. Owing to the low resistance of this bridge, the flow of current in the circuit of the source X is sufficient to energize the relay R^3 which attracts its armature 35, 125 opening the switch 34—35 and breaking the circuit of the relays R^2 and R^4 which are de-energized, releasing their armatures and disconnecting the signal controlling relay R^5 and the signal operating source B^2 , thus ex- 130

tinguishing the signal. At K^2 I show a manually operated key by which the system may be restored should the patrolman fail to respond.

5 In Fig. 2 I show a normally closed circuit police signaling system operating over the conductor 3 and ground return. An additional armature 60 is shown, controlled by relay $R^{2''}$ to operate the switch 60-61, closing a second circuit through the relay R^1 maintaining the energization thereof during the signaling interval.

10 In Fig. 3 I show a second modification. In this case the signals L' at the substations are shown normally connected from the conductor 2 to the conductor 3. The control of these signals is limited to the apparatus at the main station, the bridges being normally closed. When the subscriber responds, a circuit through relay $R^{3''}$ is completed over which this relay is energized to interrupt the circuit of relay $R^{4''}$.

15 The character and functions of the apparatus and the operation of the system of these modifications will be so clear from the description of the preferred form that I will not describe them further.

20 It will thus be seen that I show signals at the substations, consisting of lamps or other similar devices which are adapted to be operated and controlled over the conductors of the composite system, the circuits both for the operating and controlling means being governed by the attendant at the main station. I have also shown a means for automatically governing these arrangements when response is made at one of the substations.

25 While I have shown only these concrete examples of my invention, it will be obvious to those skilled in the art, that numerous and extensive departures from the forms and details of the apparatus here shown may be made without departing from the spirit of this invention, the same being herein shown solely for the purpose of clearly illustrating these embodiments.

I claim:

30 1. In a composite system, including a combined police and telephone system, the combination of a main station, a plurality of substations, police signaling devices at said stations, telephones at the substations, a plurality of conductors utilized by said devices connecting said stations, a telephone circuit operating over a pair of said conductors, lamp signals at said substations adapted to be connected in and operated over certain of said conductors, a source of current adapted to be connected with the conductors to which the lamps may be connected for operating all of said lamps simultaneously and means at the substations controlling the operation of said lamps, said controlling means connected in circuit

35 with said telephone conductors and adapted to be controlled thereover by a separate source of current located at the main station.

40 2. In a composite system, including a combined police and telephone system, the combination of a main station, a plurality of substations, police signaling devices at said stations, telephones at the substations, a plurality of conductors utilized by said devices connecting said stations, a telephone circuit operating over a pair of said conductors, lamp signals at said substations adapted to be connected in and operated over certain of said conductors, a source of current adapted to be connected with the conductors to which the lamps may be connected for operating all said lamps simultaneously and relays at the substations controlling the operation of said lamps, said controlling relays connected in circuit with said telephone conductors and adapted to be controlled thereover by a separate source of current located at the main station.

45 3. In a composite system consisting of a combined police and telephone system, a main station and a plurality of substations, a plurality of conductors connecting said stations, a telephone circuit consisting of two of said conductors, a police signaling system utilizing a conductor independent of said telephone conductors and ground, a luminous signal at each substation adapted to be connected in circuit with one of said telephone conductors and said independent conductor, a source of current for operating said lamp over said telephone conductor, means controlling the operation of said lamp, connected in circuit with said telephone conductors, said means adapted to be controlled by said main station operator.

50 4. In a composite system consisting of a combined police and telephone system, a main station and a plurality of substations, a plurality of conductors connecting said stations, a telephone circuit consisting of two of said conductors, a police signaling system utilizing a conductor independent of said telephone conductors and ground, a luminous signal at each substation adapted to be connected in circuit with one of said telephone conductors and said independent conductor, a source of current for operating said lamp over said telephone conductor, a relay controlling the operation of said lamp connected in circuit with said telephone conductors, said relay adapted to be controlled by said main station operator.

55 5. In a composite system consisting of combined telephone and police systems, a main station and a plurality of substations, telephones at said stations a plurality of conductors connecting said stations, a telephone line utilizing two of said conductors, a conductor independent of said telephone

- conductors, luminous signals at the substations adapted to be connected in circuit with one of said telephone conductors and said independent conductor, a source of current for operating said signals and means for controlling the operation of said signals, said means operated over the telephone conductors by a separate source of current located at the main station. 70
6. In a composite system consisting of combined telephone and police systems, a main station and a plurality of substations, telephones at said stations a plurality of conductors connecting said stations, a telephone line utilizing two of said conductors, a police system utilizing a conductor independent of said telephone conductors, luminous signals at the substations adapted to be connected in circuit with one of said telephone conductors and said independent conductor, a source of current for operating said signals and relays for controlling the operation of said signals, said relays operated over the telephone conductors by a separate source of current located at the main station. 75
7. In a composite system consisting of a combined telephone and police system, the combination of a main station and a plurality of substations, a plurality of conductors connecting said stations, a telephone line utilizing two of said conductors, a police line utilizing a conductor additional to said telephone conductors, police line apparatus operating over said conductors, lamps at said substations adapted to be connected in circuit with one of said telephone conductors and said additional police line conductor, a source of current for operating said lamp over said circuit and an independent source of current for operating said police line apparatus. 80
8. In a composite system consisting of a combined telephone and police system, the combination of a main station and a plurality of substations, a plurality of conductors connecting said stations, a telephone line utilizing two of said conductors, a police line utilizing a conductor independent of said telephone conductors and ground, lamps at said substations adapted to be connected in circuit with one of said telephone conductors and said police line conductor independent thereof, and a source of current for operating said lamp over said circuit, said circuit controlled from the main station. 85
9. In a composite system, consisting of a combined police and telephone system, the combination of a main station, a plurality of substations, signaling devices at said stations, a plurality of conductors utilized by said devices connecting said stations, lamp signals adapted to be operated over a circuit utilizing certain of said conductors, a source of current for operating all said signals simultaneously, means controlling the connection of said signals to said conductors and a source of current for said controlling means, said sources adapted to produce currents of distinctive characteristics. 90
10. In a composite electric system consisting of a combined telephone and police system, a main station and a plurality of substations, conductors for connecting said stations, lamp signals at said substations operated over a circuit utilizing certain of said conductors, a source of current for operating all said signals simultaneously, and means irresponsible to current of the character generated by said source, controlling said lamp circuit. 95
11. In a composite electric system consisting of a combined telephone and police system, a main station and a plurality of substations, conductors for connecting said stations, lamp signals at said substations operated over a circuit utilizing certain of said conductors, a source of current for said signals, and relays connected in circuit with two of said conductors irresponsible to current of the character generated by said source, controlling said lamp circuit. 100
12. In a composite system consisting of a combined telephone and police system, the combination of a main station, a plurality of substations, signaling devices at said stations, a plurality of conductors utilized by said devices connecting said stations, lamp signals at said substations adapted to be connected in circuit with certain of said conductors, a source of current for operating said signals over said lamp circuit, the connection of said source to said circuit being jointly controlled by electromagnetic means at the main station and a relay device located at the substations. 105
13. In a composite electric system consisting of a combined telephone and police system, the combination of a main station and a plurality of substations, conductors connecting said stations, one of said conductors utilized for the transmission of telephonic currents, a second of said conductors used for the transmission of police signal currents, lamp signals at said substations adapted to be operated over said two conductors, a source of current for operating said signals, means at the central station for connecting said source in said circuit, and means for interrupting the circuit of the police signaling system when said source is connected in circuit with said signals. 110
14. In a composite electric system consisting of a combined telephone and police system, the combination of a main station and a plurality of substations, conductors connecting said stations, one of said conductors utilized for the transmission of telephonic currents, a second of said conductors used for the transmission of police signal cur- 115
15. In a composite electric system consisting of a combined telephone and police system, the combination of a main station and a plurality of substations, conductors connecting said stations, one of said conductors utilized for the transmission of telephonic currents, a second of said conductors used for the transmission of police signal cur- 120
16. In a composite electric system consisting of a combined telephone and police system, the combination of a main station and a plurality of substations, conductors connecting said stations, one of said conductors utilized for the transmission of telephonic currents, a second of said conductors used for the transmission of police signal cur- 125
17. In a composite electric system consisting of a combined telephone and police system, the combination of a main station and a plurality of substations, conductors connecting said stations, one of said conductors utilized for the transmission of telephonic currents, a second of said conductors used for the transmission of police signal cur- 130

- rents, lamp signals at said substations adapted to be operated over said two conductors, a source of current for operating said signals, means at the central station 5 for connecting said source in said circuit and automatic means for interrupting the circuit of the police signaling system when said source is connected in circuit with said signals.
- 10 15. In a composite electric system consisting of a combined telephone and police system, the combination of a main station and a plurality of substations, a plurality of conductors connecting said stations, lamp signals at said stations adapted to be operated over a circuit utilizing certain of said conductors, a source of current, means for connecting said source in said circuit, a police signaling apparatus operating over 15 certain of said conductors, said connecting means operating to interrupt the conductors of said police signaling apparatus when said source is connected in circuit with said signals.
- 20 16. In a composite system consisting of a combined police and telephone system, the combination of a main station and a plurality of substations, conductors connecting said stations, police signaling apparatus operating over a circuit utilizing certain of said conductors, lamp signals at said substations operated over a circuit utilizing certain of said conductors, a source of current, means to connect said source in circuit with 25 said lamps, said means acting automatically to interrupt the circuit of the police signaling apparatus when the said signals are operated.
- 25 17. In a composite system consisting of a combined telephone and police system, the combination of a main station and a plurality of substations, conductors connecting said stations, signals at said stations, a source of current, means at the main station for 30 operatively connecting said source in circuit with the signals, police signal sending apparatus at said substations, signal receiving apparatus at the main station, said connecting means adapted to interrupt the circuit 35 connecting the police signal sending and receiving means and to complete a second circuit through signal receiving means when said source is connected with said signals.
- 35 18. In a composite electric system consisting of a combined telephone and police system, the combination of a main station and a plurality of substations, lamp signals at said substations, means at the main station controlling the operation of said signals, police 40 signal sending apparatus at the substations, police signal receiving apparatus at the main station, circuit connections joining said
- police signaling apparatus, said connecting means acting to interrupt said connections between the police signal sending and receiving apparatus and to make a second connection through said signal receiving apparatus when said lamp signals are operated. 65
- 45 19. In a composite system, consisting of a combined telephone and police system, the combination of a main station, a plurality of substations, conductors connecting said stations, lamp signals at said stations adapted all to be operated simultaneously over conductors of said system, a source of current at the main station for operating said lamp signals, means at the main station for connecting said source of current to said conductors, other means at the substations for controlling the connection of said signals in circuit with said conductors, a separate source of current operative simultaneously with said first named source of current to operate said other means and means for automatically retiring said signals when 70 response is made at the called station. 75
- 50 20. In a composite system, consisting of a combined police and telephone system, the combination of a main station and a plurality of substations, conductors connecting said stations, a telephone line over two of said conductors, a police signaling system over certain of said conductors, lamp signals at said substations connected between one of the telephone conductors and a police signal 80 circuit conductor, a source of current to operate said lamp signals at the main station, a separate source of current also at the main station for operating said police signaling system, and electromagnetic means at the 85 main station connecting one or the other of said sources of current to the police signal circuit conductor, and means automatically retiring said lamp signals when response is 90 made at a called substation. 95
- 55 21. In a composite system consisting of a combined police and telephone system, the combination of a main station, a plurality of substations, conductors connecting said stations, signaling apparatus at the main station normally connected in circuit with certain of said conductors, lamp signals at the substations adapted to be operated over certain of said conductors, a source of current for operating said lamp and electro-magnetic means for interrupting the normal connections of said lamp conductors and connecting said source in circuit therewith. 100
- 60 In testimony whereof I affix my signature in presence of two witnesses. 105
